[57] **CLAIM**

The ornamental design for a light fixture element, as shown and described.

DESCRIPTION

FIG. 1 is a top view of the light fixture element;
FIG. 2 is a front view of the light fixture element, wherein
the back and both side views are identical therewith; and,
FIG. 3 is a bottom view of the light fixture element;
The broken lines shown on the drawings are for illustrative
purposes only and form no part of the claimed design.
